PIN WHEEL OR THE LIKE

John Tay, 1745 Bradshaw Lane, St. Petersburg, Fla.

Filed Jan. 4, 1960, Ser. No. 58,907

Term of patent 14 years

(Cl. D34—15)

FIG. 1.

FIG. 2.

Fig. 1 is a front elevation of a Pin Wheel or the like showing my new design; and

Fig. 2 is a side elevation thereof, the handle being shown fragmentarily for convenience of illustration.

I claim:

The ornamental design for a pin wheel or the like, as shown and described.
